UNITED STATES PATENT OFFICE

SALVATORE SCIUTO, OF LAWRENCE, MASSACHUSETTS

DESIGN FOR A COMBINED FLASK AND DRINKING GLASS HOLDER

Application filed October 23, 1931. Serial No. 41,491. Term of patent 7 years.

To all whom it may concern:

Be it known that I, SALVATORE SCIUTO, a citizen of the United States, residing at Lawrence, in the county of Essex and State of Massachusetts, have invented a new, original, and ornamental Design for a Combined Flask and Drinking Glass Holder, of which the following is a specification, reference being had to the accompanying drawings, forming part thereof, in which

Fig. 1 is a top plan view of the combined flask and drinking glass holder constituting my new design;

Fig. 2 is a side elevation; and

Fig. 3 is an end elevation.

I claim:—

The ornamental design for a combined flask and drinking glass holder as shown.

SALVATORE SCIUTO.
